Application March 15, 1937, Serial No. 130,834

4 Claims. (Cl. 179—1)

My present invention relates to sound reproducer circuits of the loudspeaker type, and more particularly to a loudspeaker circuit capable of utilizing large power sources with displacement amplitudes of the mobile element of the loudspeaker limited to maximum permissible values at low audio frequencies.

The safe displacement amplitude of the driving mechanism of any given type of loudspeaker is limited to a certain maximum value. If the latter is exceeded, the coil armature, or diaphragm, strikes against stationary parts. Again, the elastic limit of the returning element, as the spring, may be exceeded thereby causing possible damage to the speaker. The electro-acoustic efficiency of commercial dynamic loudspeakers is nearly constant below 200 cycles, except at, near or below their resonance frequency. The displacement amplitude rises at the mechanical resonance frequency to a value which may be many times higher than the amplitude obtained at the same frequency for a non-resonant system. If the resonant frequency of the speaker is placed high (100 cycles or above), the maximum amplitude is usually limited by the spring or the outside seal, which may be strained with large power inputs, the moving parts do not usually strike against stationary parts. If the resonant frequency is low (60 cycles or below), the amplitude is limited by the free space for the moving coil, which may strike against stationary parts with large power inputs.

Power sources of high internal impedance, such as pentode or class B amplifiers, will emphasize these conditions as the power in the moving coil does not decrease with rising impedance (higher efficiency) of the coil around resonance. The acoustic effect of resonance is an increase (boom) in sound output around the resonance frequency and is undesirable for reproduction of high quality broadcasts, as the range of increased output is confined to a narrow frequency band. For good acoustic performance the resonance should be below the frequency range used for music and speech. A low resonance frequency restricts the power output into the speaker to certain maximum values at low frequencies without striking of the voice coil against stationary members.

Since the amplitudes of voice coil displacement must be limited to safe values at low frequencies, various devices have been used to secure such limitation. For example, a high resonance frequency has been employed to sacrifice low frequency sound output. Again, the diaphragm

area, and consequently the air load on the speaker, has been increased to reduce the amplitude of displacement; this remedy, however, affects the high frequency response. Another device which has been used in the past involves the artificial increase of the air load on the diaphragm at low frequencies by coupling it to acoustic absorption chambers which increase the air pressure at the diaphragm. Finally, the electrical input to the speaker may be limited by dividing larger powers between two or more speakers of different resonance frequencies.

It is one of the main objects of the present invention to provide a novel, and highly effective, method of compensating for the mechanical resonance of a loudspeaker; a series resonant network, tuned substantially to the mechanical resonance, being connected in shunt with the speaker to maintain the total impedance or sound output constant.

Another important object is to overcome the shift in speaker mechanical resonance to higher frequencies, due to increasing power and caused by electro-mechanical overload conditions on the loudspeaker, by using a series resonant network across the speaker input which is constructed so as automatically to trail the speaker resonance variation.

Still other objects of the invention are to improve the operating characteristics of dynamic loudspeaker network, and more especially to provide efficient and acoustically satisfactory speaker circuits which are economically manufactured and assembled.

The novel features which I believe to be characteristic of my invention are set forth in particularity in the appended claims; the invention itself, however, as to both its organization and method of operation will best be understood by reference to the following description taken in connection with the drawings in which I have indicated diagrammatically several circuit organizations whereby my invention may be carried into effect.

In the drawings:

Fig. 1 shows one form of the invention,

Fig. 2 graphically illustrates the effect of using the invention with fixed frequency resonance correction,

Fig. 3 shows speaker response curves showing the striking range when correction is used,

Fig. 4 is an audio output circuit employing another form of the invention, and

Fig. 5 shows curves similar to those of Fig. 3

when self-adjusting resonance correction is employed.

Referring now to the accompanying drawings, wherein like reference characters in the different figures designate similar circuit elements, in Fig. 1 there is shown a power output network for driving a loudspeaker of the dynamic type. The speaker is conventionally represented as including a diaphragm 1 and voice coil 2; those skilled in the art are fully acquainted with the details of constructing this type of speaker. The transformer 3 adapts the electrical speaker constants to the characteristics of the power tubes. The latter are not shown, but it will be understood that the plates thereof, assuming a push-pull output stage, are connected to the primary P. A series resonant path, including condenser 4, resistor 5 and coil 6, is connected across a portion of the primary P; although the path can be connected across the entire primary if design considerations warrant it. The resistor 5 may be the resistance of coil 6.

The series resonant network 4-5-6 functions to counteract the mechanical resonance of the speaker. The constants of the elements are adjusted to give a current rise at the mechanical resonance frequency of the speaker such that the total sound output remains constant. In Fig. 2 there is shown the effect of using a fixed frequency speaker resonance corrector network. The curves in Fig. 2 were obtained on a circuit using a medium sized speaker with a maximum power input of approximately 10 to 15 watts. The power source utilized a 227 driver and a pair of 146 type power output tubes. The curves were taken for approximately 5.5 watts input into the speaker. The transformer 3 was of commercial size and silicon steel.

Curve I of Fig. 2 shows the overall response curve of the audio network with a pure resistance load being connected across the secondary of transformer 3. The dotted curve II is the overall response of the network when the speaker is the load. However, no correction for its reactance or resonance has been made. It will be noted that at about 60 cycles there exists a resonance voltage rise due to the mechanical resonance of the particular speaker. The rise above 200 C. P. S. is due to the inductive reactance of the voice coil. Curve III shows the overall response curve for the network, including the speaker load, after correction is made for inductive reactance and mechanical resonance. It will be observed that the shunt section 4-5-6 absorbs the resonance peak at 60 cycles. The high frequency response of curve II above 200 C. P. S. is brought down by a special shunt section which comprises a condenser C₁ in series with a resistor R₁. The element 6 consisted of an iron core coil having an air gap; the coil had a fairly constant inductance.

As larger powers are used to drive a speaker, it is found that the so-called "striking" range of the voice coil near resonance is widened. Fig. 3 shows measured curves of the voltage on the primary of the coupling transformer between the plate circuit of a class B pentode stage and a loudspeaker of low resonance frequency for various constant A. C. grid voltages on the power stage versus frequency. The range of striking of the voice coil is marked. The section "violent striking" is dangerous to the speaker. This is partly due to the shift in mechanical resonance to higher audio frequencies with increasing power, and caused by electromechanical overload conditions on the loudspeaker. (See the loops in Fig. 3).

Accordingly, the shunt absorption section 4-5-6 should have a similar characteristic in order to reduce the power input to the speaker if possible, only at higher powers and at frequencies where the moving parts would otherwise strike against immobile parts of the speaker. For this purpose the saturation characteristic of steel is employed.

The inductance of an iron core coil is directly proportional to the permeability, and decreases if the B_{max.} (peak density of magnetic flux) is increased beyond 4000 gauss on high silicon steel; this determination is made by bridge measurements for the particular grade of steel. B_{max.} in turn is directly proportional to the peak magnetizing voltage, and inversely proportional to the frequency. It follows that the resonance frequency of a tuned circuit having a closed iron core inductance varies with the applied voltage, as well as with frequency. As the voltage on the speaker, and also the mechanical resonance frequency, increase with power input rise, the resonance frequency of an electrical shunt section using a closed iron core inductor will automatically trail the speaker resonance and lower the voltage by absorption of power, if by design the flux density in the inductor has increased beyond 4000 gauss to a value where the inductance decreases rapidly with increasing voltage.

In Fig. 4 is shown a power output stage using a pair of 2A5 pentodes in push-pull. The stage is of the class B type. The output transformer 9 has the voice coil 10 of the speaker across its secondary. The resonance correction network includes coil 11 and condenser 12; they are in series relation and tuned to approximately the mechanical resonance of the speaker. The condenser 13 and resistor 14 are connected in series, and both are in shunt with the series resonant network 11-12. Both series paths are in shunt across the primary P'. The condenser 13 and resistor 14 function to correct for the inductive reactance of the voice coil, as explained in connection with Fig. 1. The function of path 13-14, then, is to reduce the high audio response of the audio output network.

In a circuit of the type shown in Fig. 4 that was tested, a value of 0.25 mfd. was used for condenser 12. The choke coil 11 was of such density, and the resonant frequency of the absorption circuit 11-12 was so selected, as to secure the desired trailing action. The choke used contained approximately 0.25 lb. of silicon steel and 0.08 lb. of copper wire; this showing the relatively small cost of the correction circuit. Actual results observed with this type of circuit were as follows; (see curves of Fig. 5): For low powers (0.3 w.) the low frequency response of the speaker is excellent as substantial absorption of power by the resonance corrector takes place only below 35 cycles. For a somewhat larger power (0.7 w.) more absorption takes place below 45 cycles. At higher power levels (10 w.) the absorption of power by the network 11-12 is considerable thus preventing damage to the speaker; and commences at about 75 cycles; the resonance frequency of speaker and circuit having increased to this value due to increased voltage. Considering the increase in sound output at speaker resonance, the reproduction of low frequencies at this power level is maintained substantially constant down to approximately 65 cycles, although the voltage and power input to the voice coil are actually decreased as compared to higher frequencies. The amount of absorbed power is adjusted by the choke coil resistance.

The operating range of the iron core chokes will be in the region of steel saturation. This may give rise to a certain amount of harmonic voltages which will cause corresponding distortion of the sound output. Such distortion is of slight importance since the speaker would otherwise "strike" and produce rattling sounds. Again, the sound output at the very low frequencies is distorted anyway even at low volumes because of the insufficient baffle size at low frequencies. It is pointed out that undistorted reproduction of a 60 cycle tone requires a distance of approximately 2.8 meters from back to front of the speaker diaphragm around the cabinet. The shift of the resonance curve in the iron core corrector circuit may be such as to take care of variations of the resonance frequency of loudspeakers as occur usually in production. By employing the correction circuit of the present invention it is possible to employ a medium size, or small, loudspeaker successfully with large power inputs, and avoid a high resonant frequency with consequent gain in the reproduction of low frequencies and elimination of low frequency resonance transients ("boom"). The self-adjusting resonance frequency feature does not require careful matching of the correcting circuit and the particular speaker, thus permitting usual variations in speaker constants.

While I have indicated and described several systems for carrying my invention into effect, it will be apparent to one skilled in the art that my invention is by no means limited to the particular organizations shown and described, but that many modifications may be made without departing from the scope of my invention, as set forth in the appended claims.

What I claim is:

1. In combination with a loudspeaker of the type having a mobile diaphragm system which possesses a natural resonant frequency which varies in value with increasing power input to the loudspeaker, a series resonant circuit connected in shunt with the speaker input, said resonant circuit being adjustably tuned automatically to a frequency in the vicinity of said variable resonant frequency of the diaphragm system.

2. In combination with a loudspeaker of the type having a mobile diaphragm system which possesses a resonant frequency which varies in value with increasing power input to the loudspeaker, a series resonant circuit connected in shunt with the speaker input, said resonant circuit being adjustably tuned automatically to a frequency in the vicinity of said resonant frequency, and said circuit including reactive elements of such construction that the resonant frequency thereof changes with the power supplied thereto.

3. In combination, in an audio reproducer system, a loudspeaker of the dynamic type whose mobile system has a relatively low resonant frequency, an input transformer having its secondary coupled to the speaker moving coil, an absorption circuit, resonant to said frequency, connected across at least a portion of the transformer primary, said absorption circuit including at least a condenser in series with a choke coil, and the constants of said choke coil being so chosen that the resonant frequency of the absorption circuit varies with the power input to the transformer whereby the resonant frequency of the absorption circuit automatically trails changes in resonance frequency of said mobile system.

4. In an audio reproducer system of the type employing mobile elements having a mechanical resonance which causes rattling and striking of the mobile elements against immobile portions of the reproducer, an electrical absorption circuit coupled with the reproducer input, said absorption circuit being resonant to a frequency in the vicinity of said mechanical resonance whereby the effect of said mechanical resonance on the acoustic character of the reproducer is greatly diminished, and the constants of said absorption circuit being so chosen that changes in the frequency value of said mechanical resonance due to increased power input to the reproducer are compensated for by corresponding changes in the resonant frequency of said absorption circuit.
